UNITED STATES PATENT OFFICE.

SHOHEI IYESAKA, OF SEATTLE, WASHINGTON.

COMPUTING-MACHINE.

1,289,787.

Specification of Letters Patent. Patented Dec. 31, 1918.

Application filed May 25, 1915. Serial No. 30,276.

To all whom it may concern:

Be it known that I, SHOHEI IYESAKA, a citizen of Japan, and a resident of Seattle, in the county of King and State of Washington, have invented certain new and useful Improvements in Computing-Machines, of which the following is a full, true, and exact specification.

My invention relates to computing machines and has for its principal objects; to provide an electrically operated machine for adding, subtracting, multiplying and dividing. The more important features of my machine are magnetically operated finger keys, electrical carrying and electrically operated clearing mechanism.

Other objects will appear as my invention is more fully explained in the following specification, illustrated in the accompanying drawing and pointed out in the appended claims.

In the drawings, Figure 1 is a plan view of my device with the circuits and duplicate parts omitted. Fig. 2 is a detail perspective view of the main stationary shaft. Fig. 2a is an enlarged detail perspective section of the same to illustrate several of the cam lugs. Fig. 3 is an enlarged side elevation of a disk and attached parts with parts broken away. Fig. 4 is a part central section of Fig. 3. Fig. 5 is a similar view of another disk. Fig. 6 is a side elevation of a switch mechanism for multiplication and division. Fig. 7 is a wiring diagram for addition and subtraction. Fig. 8 is a similar diagram for multiplying and division. Fig. 9 is a similar diagram for clearing the machine. Fig. 10 is an enlarged fragmentary view of a circuit breaker in the clearing mechanism. Fig. 11 is a detail perspective view of the operating mechanism, illustrating part of the main circuits.

The computing machine of the present invention, includes four main parts, the computing cylinders and the means for manually operating them; the carrying-on means, whereby in addition or subtraction, the transfer is automatically carried out from one cylinder to the other; the clearing means, whereby all cylinders are returned to normal or zero positions, following a computing operation; and the means for carrying out the multiplying or dividing operation.

The following description will be generally confined to a similar line of division. 55

The computing cylinders and means for manually operating them.

The computing cylinders are of identical construction, being here shown as a unit cylinder, A, a tens cylinder B, a hundred cylinder C, and so on throughout the series used.

Each cylinder is composed of nine disks, here identified in accordance with the particular cylinder, as A-1, A-2, B-1, and 60 B-2, and so on throughout the series. The surface of each cylinder is provided with computing numerals 0 to 9 inclusive, and each cylinder is provided with a housing 3, formed with an opening through which a 70 particularly located numeral on the cylinder is visible.

Each disk is composed of wheels 4 and 5, the former being of less diameter than the latter and the wheels being arranged side-by-side. All wheels 4 of a cylinder are fixed upon a sleeve 6, which latter extends throughout the series of cylinders, and is mounted for rotation upon a shaft 1, fixed in any appropriate manner upon a base 2. 75 80 The sleeve is held in spaced relation about the shaft by bushings 7, and is continuously driven in either direction, at the will of the user, (one direction for addition and the opposite for subtraction), by a motor 8, 85 through suitable gearing.

Each wheel 5 has an annular series of curved bars 10 pivoted thereto at 9, the free ends of the bars interfitting, and springs 11 being arranged to hold the bars in their 90 outermost or normal positions. The curved bars are arranged to present a circular row beyond and concentric of the adjacent wheel 4, and each bar 10 has a magnetic shoe 12, adapted when forced to engage the rim of 95 the wheel 4, which rim may or may not be magnetized, to form a magnetic clutch between the wheel 5 and wheel 4 to cause the wheels 5 of the particular cylinder to revolve with wheel 4. Therefore any wheel 5 may be 100 clutched to the adjacent wheel 4 to cause a revolution of all wheels 5 of the particular cylinder.

Each wheel 4 of a cylinder is governed so as to release the magnetic clutch at a predetermined point, and as the release point of 105

each wheel 4 is different from the release point of every other wheel 4 of the particular cylinder, it is of course apparent that the extent of revolution of the particular cylinder 5 may be controlled by selection of the corresponding wheel 4. This control or operating means will now be described. Arranged in advance of the cylinders, and preferably supported on an extension 41 of the 10 housing 3, are a series of keys for manual or electrical operation. These keys are arranged one for each disk of the cylinder, and are here indicated as K-1 to K-9. The keys are identical, having their stems 15 connected, rearwardly of their pivotal supports, to bell-crank levers 40, pivotally mounted on the extension 41. The bell-crank levers are connected to pull-rods 42, carrying pivoted dogs 44, the dogs interlocking with rocks 45 on pistons 43, slidably supported in the housing 3. The pistons are held in normal positions by springs 46, and a trip 47 is arranged in the path of movement of the dog 44 to release the piston 20 after the spring 46 has been compressed. The inner end of the piston 43 underlies a hammer 18, mounted on the housing, and serving, under the blow of the piston to engage an adjacent curved bar 10 and force 25 the same toward the rim of wheel 4, to complete the magnetic clutch heretofore noted. Each key controls the magnetic clutch of its own disk, as will be evident, and if means are provided whereby each particular disk 30 may be automatically released following its step-by-step movement in accordance with the location of that disk in the series of disks in the cylinder, a particular key will be caused to rotate the cylinder to expose a 35 number through the housing-opening in accordance with that disk. For example if the sixth disk of the cylinder series (as illustrated in Fig. 3) is automatically released following its sixth step-by-step movement, 40 the movement of the cylinder if this disk is the driving disk will add six numerals to those already exposed. Therefore the cylinder may be moved any numeral-indicating distance in accordance with the driving disk 45 selected.

The automatic release means for the disks are identical for all cylinders.

Each wheel 4 is provided with ten plungers 13, arranged radially thereof, the inner ends of such plungers projecting through the sleeve 6 and overlying the shaft 7. The outer ends of the plungers have heads 15, seating in recesses 14, in the rim of the wheel 4, and each plunger is held in retracted position by a spring 16. There is thus one plunger 13 for each magnetic shoe 12, operative to force said shoe from the rim of wheel 4 and break the magnetic clutch. Arranged on the shaft 1 are lugs 60 arranged in two series 17 and 17^a, the former

for use in the addition movement of the cylinders and the latter for subtraction movement of such cylinders. The lugs 17 are disposed in a spiral row about the shaft 1, each located a particular plunger distance 70 from the hammer 18 of the particular wheel 4. That is to say, the lug 17 for the first plunger wheel will be located one plunger to the left of the hammer controlling the magnetic shoes of that disk, the second lug 75 17, two plungers to the left of the hammer for the second disk, and so on. Therefore if the first disk is magnetically clutched it will only move one step before the lug 17 will engage or be engaged by the plunger to 80 break the magnetic clutch, and stop the cylinder. Therefore the selected key operated will govern the number of step-by-step movements the cylinder will make before stopping, and hence said cylinder may be 85 moved any desired numerals.

The lugs 17 control movement of the disks in one direction and the lugs 17^a control the movement in the opposite direction. These lugs are therefore opposed, and they 90 are preferably pivotally mounted in recesses in the shaft 1, as shown in Fig. 3, so that the set not in use will be tilted out of the way by the moving plungers without affecting said plungers.

In connection with the cylinders and the operating means, it is deemed advisable to here describe the means for preventing overrunning of the cylinders, that is holding them in proper numeral displaying position. 100 The wheel 5 of the final or ninth disk of each cylinder, which wheel 5 is preferably wider than the remaining wheels 5 of the cylinder, is provided with ten armature blocks 28, spaced thereon in accordance with 105 the spacing of the numerals on the cylinder. A magnet 29 is arranged on each housing to be engaged by each block 28. The magnet 29 is in a circuit 31 having a source of energy 30, and having a switch-break controlled by 110 the dog 44 of the key mechanism. When the key is operated, the holding circuit is broken and the cylinder free to move, while with the key in normal or inoperative position, the magnet 29 acts as a retarder to the 115 cylinder, and upon release of the magnetic clutch will hold the cylinder in proper numeral-exposing position.

The carrying-on means.

The computing numerals are from 0 to 9 on each cylinder, so that in any computation the numbers applied to the units-cylinder, in addition for example, in excess of nine in total must be automatically carried on or 125 presented on the next cylinder.

For the carrying-on operation, each cylinder is identically constructed, being provided with means to cause the next successive cylinder to be automatically operated when 130

necessary. Of course as the computing numerals are added by a step-by-step movement, the carrying on to the next cylinder will be by single digits, and hence only the 5 first, or single movement disk of each cylinder will have to be automatically actuated.

The housing of each cylinder above each wheel 5 is provided with a circuit closer in the form of spaced spring strips. As the 10 carrying-on is identical, except as to direction in both addition and subtraction, and multiplication and division, the wheels 5 are arranged to coöperate with two circuit closers, one 19^a for addition and the other 15 20^a for subtraction. The wheels 5 are provided with radially projecting circuit closing plugs, one set 19 for addition and to engage circuit closers 19^a, and the other 20 for subtraction to engage circuit closers 20^a. The 20 circuit closers are spring strips depending into the path of movement of the plugs, the strip first to be engaged in the operative movement of the plug being of greater length than the other, so that the circuit is 25 closed at this point in operative movement of the plug in the proper direction, but not closed in the movement of the plug in the opposite direction.

The plugs 19 and 20 are arranged on the 30 particular wheels 5 with relation to the possible numeral-setting movement of that wheel. For example the plug 19 for the first or A—1 disk will be in line with the plugs of that disk opposite or in registry 35 with the computing numeral 0, continuing in similar relation to ninth disk, but increasing in direct proportion as the increased step-by-step movement possible of such disks, that is two such plugs for the second disk 40 and so on. The plugs 20 are directly reversed, there being one for the ninth disk, two for the eighth, and so on. The plug 20 for the ninth disk is of course opposite or in registry with the computing numeral 9.

The 45 circuit closers 19^a control circuit 19^b which include electro-magnets of the keys operating the first disk of the next cylinder in advance, such electro-magnets being here indicated as 21—A, 21—B, 21—C, etc. These 50 electro-magnets when energized operate the particular key, and so operate disk one of the particular cylinder to carry-on the number to such advance cylinder. The circuits 19^b and 20^b, in addition to being 55 broken at the particular circuit closers 19^a and 20^a are also broken at the key for each disk, a switch 48, being here included, normally open, and closed momentarily when the key is operated. (See Fig. 3.) Thus, 60 when a key is operated, one break in the circuit is closed, and if a plug 19 or 20 (as in addition or subtraction) is in position to close the other break, a carrying-on operation is perfected, otherwise no operation occurs.

From the above it will be understood, that if the first cylinder indicates 9, and one is to be added, the depression of the key for the first disk of said cylinder closes the carry-on circuit at 48, and the plug 19 of 70 said first disk closes the circuit closer 19^a of such disk. The key of the first disk of the second cylinder is operated, and the numeral 1 exposed thereon, while the disk of the first cylinder has moved such cylinder 75 one step, or to indicate the 0.

The arrangements of the carry-on circuits is shown in Fig. 7. The plugs 19 and 20, the circuit-closers 19^a and 20^a, and the circuits 19^b and 20^b are here shown as common. 80 All circuits have a common circuit wire 50 and source of energy 51. The switches 48 of one cylinder have a common wire 52 on one side, which leads to the electro-magnet 21 to the next advance cylinder, the other 85 side of each electro-magnet having a lead 53 to a common circuit wire 54.

The clearing mechanism.

Following a computation, it is necessary 90 to clear the machine, that is return all cylinders to 0 indication. On each ninth or final disk of each cylinder is a row of plugs 22, one being opposite each plunger of such disk except the 0 plunger. These plugs operate circuit closers 23 and circuits 24, the said circuits including the electro-magnets 21. The said circuits are in a common circuit 95 25, having a source of energy 26 and controlled by a switch 27. When clearing is 100 desired, the switch 27, is closed, and the closing of the circuit on the cylinders will operate the magnets 21 thereof to advance 105 said cylinders. The movement of the cylinders will continue as long as new plugs 22 are positioned to close the said circuits. This will continue until each cylinder reaches 0 position. As there is no plug 22 at this position the circuit remains broken and the cylinder remains at rest. The 110 movement will continue automatically until all cylinders are in 0 position, or cleared.

The multiplication and division mechanism.

Multiplication or division is simply addition or subtraction carried out an indicated 115 number of times, as 3x3 is simply 3 added 3 times. If therefore, as is provided in the present machine, means may be provided for carrying out, automatically, the indicated 120 number of additions (or subtractions) the process of multiplication (or division) may be readily accomplished.

For this purpose each key in addition to the key of the first disk of each cylinder, is provided with an operating magnet, here 125 indicated as 32 to 39 for each set of keys, the magnets of the keys of each cylinder being distinguished from the magnets of the keys of the other cylinders by the addition of the letter of such cylinder. 130

Example of addition.

The magnets 32—A to 39—I inclusive, are used only in multiplication, and division, to operate their respective keys. In addition to the elements and mechanism already described, there is necessary for multiplication and division a switch cylinder M, which is mounted upon a shaft 56, with which it revolves only when thrown into engagement by a clutch 57 and hand lever 58. The switch cylinder M is driven by gears 59 and 60 from the sleeve 6, at a speed of one ninth the speed of cylinders A, B, etc. The switch cylinder M is divided into the same number of divisions *a*, *b*, *c*,—*i*, as there are cylinders A, B, C,—I. The divisions *a* to *i* each have switch closing plates 61 varying in number from one for *a* to nine for *i*, all of which are equally spaced so far as they go around the periphery of cylinder M. There are nine switches 62—*a*, 62—*b*—to 62—*i* which are arranged in line with divisions *a*, *b*, *c*, etc., and are adapted to be closed by the plates 61 as the cylinder M revolves. Switches 62—*a* to 62—*i* are connected in circuits with a common source 63 (Fig. 8) by a wire 64 and a switch 65 which is closed when the clutch 67 is thrown into engagement and to a set of plugs P—1, P—2—P—9 respectively, by wires 66.

Plugs P have the usual flexible connections and are adapted to be inserted into plug holes H—1, H—2—H—9. There may be several plugs P and holes H from the same wire so as to facilitate their use for numbers which contain more than one digit of the same denomination. The plugs P—1 to P—9 represent digits 1 to 9 respectively, and the holes H—1 to H—9 represent places from unity to nine. The holes H—1 to H—9 are connected to one terminal of all of the switches 19—*a* and 20—*a* on cylinders A to I respectively by wires 68 (shown only in Fig. 8).

From the other terminals, wire 69 leads to the various magnets 21—A to 39—I respectively, the switches on each disk being connected to the particular magnet beneath the key for operating that disk. Wires 70—*a* to 70—I connect all of the wires 69 from each cylinder A to I, respectively, to switch plug holes Q—1 to Q—9 respectively. Other wires 71, 72, etc., to 79, connect the remaining terminals of the magnets 21—A to 21—I to a switch plug R—I. The other magnets 32—A to 39—I are similarly connected by wires 72 to 79 respectively to plugs R—2 to R—9.

60 The Q—I to Q—9 holes have terminals Q—1 to Q—9 respectively, which are arranged on a circular strip 80 (Figs. 1 and 6). A traveling switch 81 is mounted on an arm 82 which is attached to a shaft 83, 65 which in turn is driven by gears 84 and

84—*a*, at one-ninth the speed of the switch cylinder M. As the traveling switch revolves, it closes in turn all of the terminals *q*—1 to *q*—9 successively with a wire 85 which leads to source 63, thus completing 70 the circuits.

It will be noted that the circuits just completed have each five breaks or switches besides the switch 65. It is thus seen that many combinations of circuits are possible 75 by use of the plug and hole switches and the traveling switch in addition to the switches on the disk wheels and the switch cylinder M. It will be noted that the switch cylinder M and the traveling switch mechanism are positively geared together and that the traveling switch is always making contact between some one of the terminals *q*—1 to *q*—9 and the source 63. As previously noted, the operation of division is 85 accomplished by reversing the direction of rotation of the entire operating mechanism. The steps or process of multiplication will be best understood by citing an example.

Assume the following multiplication 90 364×843 which may be rewritten:

$$\begin{array}{r} 36,400 \times 8 \\ 6,400 \times 4 \\ 364 \times 3 \end{array}$$

95 The first step is to determine the number of places of the product. A common rule is to add the number of places in both multiplier and multiplicand and subtract one which in this example, will give five places or the 100 10,000 cylinder. This cylinder is represented by H—5 hole, and as the first number is 3, the P—3 plug should be inserted in the H—5 hole. Dotted lines on Fig. 8 show the connections to be made. This connection establishes the 300,000 figure. Next and for similar reasons, insert the P—6 plug in the 1,000 place or H—4 hole which establishes the 6,000 figure. Next insert plug P—4 in the 100 place or H—3 hole which establishes the 400 figure. The numbers referred to are now set and the multipliers may be arranged by placing the 8, 4 and 3 or R—8, R—4, and R—3 plugs in the third, second and first or Q—3, Q—2 and Q—1 places or 110 115 holes respectively.

We have now established the complete setting for making the multiplication of the first set numbers by the second ones set. The lever 58 is now thrown to the left which 120 closes the clutch 57 and switch 65, thus starting the switch cylinder M and connecting the source 63 into the lines. The revolving of the cylinder M at the rate of one closing plate to each complete revolution of the 125 wheels 4 thus making all connections between the switches 62—*a* to 62—I, during the complete revolution of cylinder M, each connection being held through one complete revolution of the wheels 4. The current 130

flowing through wires 66 flows through the plug and hole connections above and into the switches 19—*a* and 2—*a* of the particular cylinders to which connections are made, *i. e.*, C, D and E. The plugs 20 only close the switches 20—*a* and thus allow the current to flow on to wires 69 and to the various magnets, and also to the holes Q—1, Q—2 and Q—3 respectively, which are wired to the cylinders C, D and E respectively. The current now passes through the connections previously made to the other terminals of magnets which are connected to plugs R—8, R—4 and R—3. The traveling switch completes the connections and the circuits at Q—3, Q—2, Q—1 to the source 63. As the cylinder M makes one complete revolution, connections are made three times on the *c* division, six times on the *f* division and four times on the *d* division.

Through the plug and hole connections above and below, the K—8 keys of the C, D and E cylinders are magnetically operated four, six and three times respectively when the circuits are closed by the traveling switch when it is opposite the hole Q—3. Upon the next revolution of the cylinder M, the K—4 keys of the B, C and D cylinders are similarly operated a similar number of times when the circuits are closed by the traveling switch when it is opposite hole Q—2. Upon the third revolution of the cylinder M, the K—3 keys of the A, B and C cylinders are similarly operated a similar number of times when the traveling switch is at hole Q—1, thus completing the multiplication.

What I claim as new and desire to protect by Letters Patent, is—

1. In a computing machine, the combination of a plurality of manually and electrically operated digit cylinders, electrically operated carrying means, whereby digit carrying from one digit cylinder to the next higher digit cylinder is effected, means for normally holding any or all cylinders against movement, and electrically operated means for clearing or returning all cylinders to a zero position.

2. In a computing machine, the combination of a plurality of digit cylinders, each including a plurality of two part disks, power means for operating one part of each of the said disks in either direction, manually and electrically operated means for causing the other parts of the said disks to operate in conjunction with the first mentioned part a predetermined part of a complete revolution, means upon the second mentioned parts of the disks for closing electrical circuits which furnish current to electrically operated means for causing the two parts of disks in other cylinders to operate in conjunction, whereby units carry-

ing from one cylinder to the next is effected electrically operated means for holding the second mentioned parts of the disks of any cylinder against movement, except when operating in conjunction with the first mentioned parts of the disks, and electrically operated means for returning all cylinders to a zero position.

3. In a computing machine, the combination of a plurality of digit cylinders, each including nine disks, each disk having a wheel which is secured to a common sleeve, the said sleeve being adapted to be driven in either direction from a source of power, a loose wheel for each disk, all loose wheels in a given cylinder being adapted to operate in unison, electrically controlled means for causing the loose wheels of the disks to revolve as a unit with the fixed wheels, mechanically actuated means for releasing the loose wheels from the said electrically controlled means at a predetermined point, means upon each loose wheel for closing stationary switches a predetermined number of times for each complete revolution of the said loose wheels, whereby an electrical circuit is completed to a magnetic coil, means actuated by the said magnetic coil for causing the loose wheels of an adjacent cylinder to revolve one tenth of a complete revolution, whereby the 1st mentioned cylinder is caused to carry to the next digit.

4. In a computing machine, the combination of a plurality of digit cylinders, each including nine disks, each disk having a wheel which is secured to a common sleeve, the said sleeve being adapted to be driven in either direction from a source of power, a loose wheel for each disk, all loose wheels in a given cylinder being adapted to operate in unison, electrically controlled means for causing the loose wheels of the disks to revolve as a unit with the fixed wheels, mechanically actuated means for releasing the loose wheels from the said electrically controlled means at a predetermined point, means upon each loose wheel for closing stationary switches a predetermined number of times for each complete revolution of the said loose wheel, whereby an electrical circuit is completed to a magnetic coil, means actuated by the said magnetic coil for causing the loose wheels of an adjacent cylinder to revolve one-tenth of a complete revolution, manually operated circuit selecting means, whereby various combinations of circuits may be built up, mechanically operated means for closing contact switches in the last mentioned circuits a predetermined number of times, whereby the last mentioned cylinder is caused to carry to the next digit.

SHOHEI IYESAKA.
